DESIGN FOR A COMBINED RUFFLE DISPLAY AND CONTAINER UNIT OR THE LIKE

John T. Wright, West Warren, Mass., assignor to The William E. Wright & Sons Company, a corporation of New Jersey

Application August 1, 1940, Serial No. 94,126

Term of patent 3½ years

To all whom it may concern:

Be it known that I, John T. Wright, a citizen of the United States of America, residing at West Warren, county of Worcester, State of Massachusetts, have invented a new, original, and ornamental Design for a Combined Ruffle Display and Container Unit or the like, of which the following is a specification, reference being had to the accompanying drawing, forming a part thereof.

The figure is a perspective view of a combined ruffle display and container unit or the like, showing my new design.

I claim:

The ornamental design for a combined ruffle display and container unit or the like, substantially as shown.

JOHN T. WRIGHT.
